E. M. BAILEY

SHADE AND CURTAIN BRACKET

Filed Sept. 13, 1927

UNITED STATES PATENT OFFICE.

ELMER M. BAILEY, OF HAVENSVILLE, KANSAS.

SHADE AND CURTAIN BRACKET.

Application filed September 13, 1927. Serial No. 219,277.

This invention aims to provide a novel means whereby a shade and curtain bracket may be held on window frames of different dimensions.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

In the drawings:—

20 Figure 1 shows in front elevation, a device constructed in accordance with the invention;

Figure 2 is a longitudinal section on the line 2—2 of Figure 1;

25 Figure 3 is a rear elevation;

Figure 4 is a front elevation wherein the latch has been swung to open position;

Figure 5 is an end elevation;

30 Figure 6 is a cross section on the line 6—6 of Figure 1; and

Figure 7 is a cross section on the line 7—7 of Figure 1.

The device includes a first member 1, in the form of a plate, the structure, preferably, being made of metal throughout. The first member 1 is provided along its longitudinal edges with overhanging guide flanges 2. The first member 1 is supplied at its ends with brackets 3 adapted to support curtain poles or the like. At one end of the member 1 is located a rearwardly extended arm 4, arranged approximately at right angles to the member 1, the corners of the arm 4 being turned to form projections 5. The arm 4 has 40 a rectangular extension 6 which is secured to the rear surface of the member 1, the extension 6 being retained within the guide flanges 2, as Figures 7 and 3 will show.

The device includes a second member 7 in 50 the form of a plate, mounted to slide within the guide flanges 2 of the first member 1. The second member 7 is supplied at its ends with an angularly disposed arm 8, corresponding to the arm 4, the arm 8 having projections 9, like the projections 5. The arm 8 is equipped with a concaved boss 10 having a

slot 11 adapted to receive one trunnion of a shade roller (not shown).

The second member 7 carries a keeper 12, in the form of a headed stud, mounted to move in a slot 14 formed in the first member 1. A headed pivot element is mounted to move in the slot 14. On the pivot element 15 a latch 16 is mounted to swing, in parallelism to the first member 1. The latch 16 has any desired number of inclined seats 17, adapted to be engaged, one at a time, with the headed stud 12. The latch 16 has an angularly projecting end 18. The numeral 19 marks a retractile spring. One end of the 70 retractile spring 19 is attached at 20 to the part 18 of the latch 16, and the opposite end of the spring is attached at 21 to the first member 1.

When the parts are arranged as shown in 75 Figure 1, the spring 19 tends to hold the latch 16 from swinging on the pivot element 15, the keeper 12 being held engaged with one of the seats 17. The spring 19 tends to draw the second member 7 to the left in Figure 2, 80 and, thus, one of the stiles of a window frame (not shown), may be gripped between the projections 5 and 9, the article thus being held on the window frame for the support of one end of a curtain rod or the like. The 85 latch 16 may be swung into open position, as shown in Figure 4, and the second member 7 may be slid lengthwise, thereby to adjust the device for window frame stiles of different widths, the latch 16 then being swung 90 down to engage the keeper 12 in the appropriate one of the seats 17 in the latch 16. The latch 16 may be engaged at different points (represented by the seats 17) with the stud 12, and, therefore, with the second member 95 7, and, thus, the pull of the spring 19 may be kept approximately constant, even though the device may have been adjusted to accommodate window stiles of different widths. In other words, the construction is such that 100 the spring 19 will not exert a weak pull when the article is mounted on a narrow window stile, and exert an objectionably strong pull when the article is mounted on a wide window stile.

105 What is claimed is:—

1. A device of the class described comprising first and second frame-engaging members connected for right-line sliding movement, the second member having a keeper, a pivot element mounted for right-line sliding movement on the first member, a

latch mounted to swing on the pivot element and engageable with the keeper, and a spring connection between the latch and the first member.

5. 2. A device of the class described comprising first and second frame-engaging members, the first member having an elongated opening, the second member having a keeper

movable in the opening, a pivot element movable in the opening, a latch mounted to swing on the pivot element and engageable with the keeper, there being a spring connection between the latch and the first member. ¹⁰

In testimony that I claim the foregoing as my own, I have hereto affixed my signature.

ELMER M. BAILEY.
